VACUUM CLEANER WITH MOTOR AND
HANDLE PIVOTED ON CASING

Edgar P. Turner, Fanwood, and Charles J. Stockburger, North Plainfield, N. J., assignors to The Singer Manufacturing Company, Elizabeth, N. J., a corporation of New Jersey

Application December 11, 1948, Serial No. 64,736

4 Claims. (Cl. 15—323)

1

This invention relates to vacuum cleaners and it has as its primary object to provide an improved frame construction that can easily be manufactured and conveniently assembled.

A further object of the invention is to provide an improved casing construction that provides easy access to the various moving parts of the vacuum cleaner mechanism, whereby they can easily be cleaned, adjusted or repaired.

Another object of the invention is to provide an improved means for mounting a cord take-up reel and a motor in the handle of a vacuum cleaner.

A still further object of the invention is to provide a vacuum cleaner having improved structural features.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be understood by those skilled in the art.

In the drawings:

Fig. 1 is a front perspective view of a vacuum cleaner embodying the invention, it being understood that the front face of the upstanding vacuum cleaner handle is provided with an expanded metal grille similar to the three small areas indicated thereon.

Fig. 2 is a rear perspective view of the vacuum cleaner shown in Fig. 1, it being understood that the hinged door is provided with a complete panel of expanded metal.

Fig. 3 is a top plan view of portions of the vacuum cleaner shown in Figs. 1 and 2, the covers shown in Figs. 4 and 5 having been removed.

Fig. 4 is an upside down view of a cover for a portion of the open cleaner shown in Fig. 3.

Fig. 5 is an upside down view of a second cover for another portion of the open cleaner shown in Fig. 3, and

Fig. 6 is a sectional view of the vacuum cleaner handle taken substantially on the line 6—6 of Fig. 1.

Referring more specifically to the drawings, the invention is disclosed as embodied in a vacuum cleaner having a lower casing shell 16, an upper casing shell or cover 17, a lower motor housing 18, an upper motor housing or cover 19, and a propelling handle, indicated generally by the numeral 21, the handle having a hand grip portion 22 at its free end. As best seen in Figs. 55

2

1 and 2, the upper casing shell or cover 17 is complementary to and covers the lower casing shell 16, and the upper motor housing or cover 19 is complementary to and covers the lower motor housing 18.

The lower casing shell 16, has a pair of rear support wheels 20, and as best seen in Fig. 3 is in the form of a U-shaped box, which has a forwardly positioned upwardly open nozzle cavity 23, and a pair of upwardly open air duct cavities 24a and 24b. The nozzle cavity 23 has an open bottom portion 25, which forms a suction mouth 26, the latter being divided into three separate openings by a pair of rug hold-down bars 27—27. The air duct cavities 24a and 24b extend rearwardly from the nozzle cavity 23. Inner walls 28a and 28b of the air duct cavities 24a—24b are provided respectively with semi-circular openings 29a and 29b. Outer walls 31a and 31b of the air duct cavities each have an infacing boss 32, upon which are pivotally mounted the ends of brush support arms 33a and 33b. The free ends of the arms 33a and 33b rotatably support a dust brush 34, which may be of well known construction. The lowermost part of the duct cavities 24a and 24b are closed respectively by bottom walls 35a and 35b and the nozzle cavity 23 is bounded by a forward wall 36 and a rear wall 37. A resilient bumper 38 extends along the outer face of the walls 23, 31a and 31b.

The lower motor housing 18, as best seen in Figs. 2 and 3, is in the form of a semi-cylindrical box and has an outer semi-cylindrical wall 44. The semi-cylindrical box is divided into a plurality of cavities 39, 40, 41, 42 and 43 by vertical walls 46, 47, 48 and 49. The cavities 39 and 43, located adjacent the sides of the housing 18, are substantially semi-cylindrical in form and each cavity 39 and 43 forms the lower half of a casing for fans 50a and 50b. The cavity 40, which is separated from the fan cavity 39 by the wall 46, houses the lower half of a ball bearing 51a that rotatably supports a horizontally extending motor shaft 52. The ball bearing 51a is covered by a screw held cap 53a. The wall 47, between the cavity 40 and the cavity 41, is cut away to accommodate the lower half of a motor ventilating fan 54 carried on the shaft 52. The cavity 41 houses field coils 56 and an armature 57 of the vacuum cleaner motor. The means for mounting the field coils etc. forms the basis of a patent application Serial No. 75,552, filed February 10, 1949, now Patent No. 2,613,242, dated October 7, 1952, and will not herein be described. The cavity 42, which is bounded by the walls 48 and 49,

houses a pair of carbon brushes 58—58 and a ball bearing 51b which is mounted in a manner similar to the ball bearing 51a previously described.

The wall 59a, which forms the outer boundary of the fan chamber 39, is apertured by a semi-cylindrical hole 61a, which accommodates the smaller diameter portion of a flanged ring 62a. The flange of the ring 62a enters a semi-annular recess 63a formed in the face of the semi-cylindrical opening 29a of the shell 16. In like manner the wall 59b for the chamber 43 has a semi-cylindrical hole 61b for the smaller portion of the ring 62b. Also the flange of ring 62b enters a semi-annular recess 63b in the face of the opening 29b. The two rings 62a and 62b, when clamped in place by the cover 17 and the cover 19, presently more fully to be described, function as pivots for the motor members 18 and 19 and for the pivotally mounted handle 21.

The motor shaft 52, in addition to carrying the armature 57 and the ventilating fan 54, carries the fans 50a and 50b at its opposite ends. The hub of the fan 50b is extended and forms a pulley for driving a belt 60 which drives the dust brush 34.

The lower motor housing 18 has an extension 64 formed integral therewith. This extension 64 is positioned tangentially with respect to the motor housing 18 and a lower portion of the extension is apertured by a pair of converging ducts 66a and 66b, the forward ends of duct 66a being connected with and extending rearwardly from the fan cavity 39, whereas the forward end of duct 66b is connected with and extends rearwardly from the cavity 43. The upper portion of the extension 64 provides a shelf on which is rotatably mounted an electric cord take-up reel 67 rotating on an axle 70 that is perpendicular to a plane containing the motor axle 52.

The lower casing shell 16 is closed by the complementary casing cover 17, and this cover, which is best seen in Fig. 4, is in the form of a U-shaped box. The cover 17 has at its forward end a nozzle covering cavity 123 and a pair of rearwardly extending duct covering cavities 124a and 124b. The cavity 123 is complementary to the cavity 23, and the cavities 124a and 124b are respectively complementary to the cavities 24a and 24b. The cavity 123 is covered with a top wall 125. The cover 17 also has a plurality of walls 128a, 128b, 131a, 131b, 135a, 135b, 136 and 137, that are complementary respectively to walls 28a, 28b, 31a, 31b, 35a, 35b, 36 and 37 of the shell 16. The walls 128a and 128b are each provided with a semi-cylindrical opening, designated as 129a and 129b, which are complementary to the openings 29a and 29b of the walls 28a and 28b.

The lower motor housing member 18 is closed by the complementary casing cover 19. The cover 19, which is best seen in Fig. 5, has a plurality of cavities and walls which are complementary to similar parts formed in the motor housing 18. For example, the cavities 139, 140, 141, 142 and 143 in the cover 19 are complementary to cavities 39, 40, 41, 42 and 43 in the motor housing 18. Also the walls 144, 146, 147, 148 and 149 of the motor cover 19 join walls 44, 46, 47, 48 and 49, respectively, of the motor housing member 18. Also the end walls 159a and 159b of the cover 19 join end walls 59a and 59b on diametral lines, each of the walls 159a and 159b being provided respectively with a semi-cylindrical recess 161a—161b that are complementary to the recesses 61a and 61b. Each recess 129a and 129b of the cover 17

is provided respectively with a semi-annular recess 163a and 163b for accommodating the flange portion of the rings 62a and 62b, and the recesses 161a and 161b of the cover 19 engage the small collar of the rings 62a and 62b. The motor cover 19 also has an extension cover 164 that is complementary to the extension 64. The motor cover 19 is held to the lower motor housing member 18 by means of a plurality of screws 170 that pass through appropriate holes 171 in the cover 19 and are threaded into holes 172 in the motor housing member 18.

The casing cover 17 is held to the shell 16 by a strap spring 173. This spring is pivotally supported from a pair of upstanding arms 174—174 which in turn are supported from a pair of horizontally disposed lugs 176—176 formed integral with the lower shell 16. The free end of the spring 173 is provided with a hole 177. When the cover 17 is in place on top of the shell 16, the arms 174—174 extend through an opening 178 formed in the upper wall 125 and the spring 173 is flexed down over the top of the cover 17 to which it is securely held by a screw 179.

The box-like handle 21, which along with the motor housing members 18 and 19 is mounted to pivot on the flanged rings 62a and 62b, is rectangular in cross section. The size of this rectangular cross section is large near the motor housings 18 and 19, and gradually decreases in size as the hand grip 22 is approached. This handle 21 (Figs. 2 and 6) is constructed from a pair of converging side angle-plates 181a and 181b, the lower ends of which are held to the extension 64, of the motor housing 18, by a plurality of screws 182. The upper end of the plates 181a and 181b are held to the hand grip 22 by screws 183. A channel or U-shaped cover 184 is held to the extension 64 by a bracket 185 and screws 186. Removal of the cover 184 exposes to view the cord reel 67, hereinbefore described. The major portion of the face of the handle 21 is covered with an open grille work 187, which as illustrated is made of a sheet of expanded metal formed into a U-shaped grille. The back of the handle 21, is closed by a door 188 having a single grille panel 189 made from expanded metal. This door is hinged to the angle plate 181b, as at 191 and is provided with a latch 192 of known construction.

The two exhaust ducts 66a and 66b converge into a single duct 193 which extends upwardly into the handle 21. The open end of this duct is provided with a means (not shown) whereby a dust bag 194 is attached to the end of the duct 193, it being understood that access to the open end of the duct 193 and to the dust bag 194 is had through the opening provided by the door 188. The grilles 187 and 189 provide sufficient ventilation so that filtered air can escape from the bag 194 to the atmosphere.

An electric cord 196 is wound around the reel 67 and the end of this cord extends upwardly through the handle 21 to an outlet 197 found in the hand grip 22. The uppermost end of the cord 196 is fitted with an electric plug 198.

The hand-grip 22 is also provided with an electric switch 199 by which the motor of the vacuum cleaner can be started or stopped. The hand-grip 22 also has a button 200, which, by means of a rod and latch (not shown) provides a means for latching the handle 21 in a plurality of selected positions.

The vacuum cleaner of the present invention 75 can be assembled in the following simplified man-

5. First, the various motor and fan elements, including the field coil 56, the armature 57, brushes 52-53, bearings 51a-51b, and fans 5a-50b are assembled in the lower motor housing 18. This can very easily be done because 5 the mountings for these units are open to view. Also, with the cover 184 removed, the cord reel 67 can be readily mounted on the extension 4. When this has been accomplished, the motor housing cover 19 is attached to the lower housing 18 by means of screws 179, and the cover 184 is attached to the extension 64 by means of screws 86. Thereafter, the rings 62a and 62b are slipped 10 onto opposite ends of the motor housings 18-19 and the flanges of these rings are placed into the semi-circular recesses 63a-63b formed in the lower casing shell 16. Then the dust brush 34, by means of arms 33a-33b, is supported from the bosses 32-32, at the same time making certain that the belt 60 is properly installed. Thereafter the cover shell 17 is placed over the shell 16 in such a manner that the flanges of the rings 62a-62b enter the recesses 163a-163b of the openings 129a-129b. Then the hinged spring 173 is bent down over the top surface of the shell 15 cover 17 and held thereto by the screw 179.

The dust bag 184 is very easily attached to the single duct 193 by opening the door 188. After the bag 184 is in place the door 188 is closed and secured by the latch 192.

While the wires connecting the motor 56-57-53 to the reel 67 are not shown, it will be obvious to one skilled in the art that there is no need for flexible cord connections between the motor 56-57-53 and the reel 67. This results from the fact that the motor and the reel are both mounted on the integral parts 18-64. Furthermore, the method of mounting the reel 67 with respect to the motor 56-57-53 permits of the best utilization of space. The greatest dimension of the motor is the longitudinal length of the shaft 52, and the greatest dimension of the reel 67 is its diametrical dimension. It will be noted that both of these are transverse of the cleaner and the handle.

Having thus set forth the nature of the invention, what we claim herein is:

1. A vacuum cleaner casing construction comprising, a lower casing shell having a forwardly positioned nozzle cavity and a pair of rearwardly extending air duct cavities open to said nozzle cavity, an upper casing shell having a nozzle cavity and a pair of rearwardly extending air duct cavities complementary to cavities in said lower casing shell, means for holding said upper shell to said lower shell, a pair of flanged rings clamped between said two shells at locations rearward of such nozzle cavities and adjacent the rear ends of said air duct cavities, a lower motor housing having a pair of rearwardly extending converging ducts, an upper motor housing separable from and complementary to said lower motor housing, means for pivoting said motor housings on said flanged rings, and a handle secured to said motor housings.

2. A vacuum cleaner casing construction comprising a lower casing shell having a forwardly positioned nozzle cavity and a pair of rearwardly extending air duct cavities open to said nozzle cavity, an upper casing shell having a nozzle cavity and a pair of rearwardly extending air duct cavities complementary to cavities in said lower casing shell, means for holding said upper shell to said lower shell, a pair of flanged rings clamped between said two shells at locations rear-

ward of such nozzle cavities and adjacent the rear ends of said air duct cavities, a lower motor housing having a pair of rearwardly extending converging ducts, an upper motor housing complementary to said lower motor housing, a pair of complementary semi-cylindrical holes in opposite sides of said upper and lower motor housings, the motor housing walls defining said holes being arranged to slidably engage said flanged rings thereby allowing said motor to rotate relative to said upper and lower casing shells, a handle secured to said motor housings, a cord take-up reel carried by said handle, and an electric cord extending from said reel to the end of said handle.

3. In a vacuum cleaner, a two-part ambulatory casing arranged to be moved over a floor being cleaned, means for holding said two-part casing together, an electric motor having a horizontally positioned shaft, means for pivotally mounting said motor with respect to said ambulatory casing, a pair of fans located on opposite ends of said motor shaft, a box-shaped handle rigidly secured to said motor, a cord reel carried within said box-shaped handle and having its maximum dimension extending in a direction parallel to the motor shaft, a pair of convergent exhaust ducts extending longitudinally of said handle and receiving air blown from said fans, a dust bag connected to said ducts and housed in said handle, and grille work forming part of said handle and allowing filtered air to escape from said bag.

4. A vacuum cleaner comprising a lower casing shell having a forwardly positioned nozzle cavity and a pair of rearwardly extending air duct cavities open to said nozzle cavity, an upper casing shell having a nozzle cavity and a pair of rearwardly extending air duct cavities complementary to cavities of said lower casing shell, means for holding said upper shell to said lower shell, a motor-handle unit pivotally mounted with respect to said casing shells, the axis of said motor extending transversally with respect to the longitudinal dimension of said handle, a cord reel carried by said handle, said reel having its axis normal to a plane containing the axis of said motor, a pair of fans driven by said motor, a box-shaped member forming the outer shell of said handle, a pair of convergent exhaust ducts extending longitudinally of said handle and receiving air blown by said fans, a dust bag carried within said box-shaped handle and connected to receive air from said ducts, and grille work forming a part of said box-shaped member and allowing filtered air to escape from said bag.
